(57) **CLAIM**

The ornamental design for a front face of a window covering, as shown and described.

DESCRIPTION

FIG. 1 is a front elevational view of a front face of a window covering showing my new design, the front face of a window covering being shown in an open, pulled-up position.

FIG. 2 is a side elevational view of the front face of a window covering of FIG. 1.

FIG. 3 is a front elevational view of the front face of a window covering of FIG. 1, shown in a partially closed position.

FIG. 4 is a side elevational view of the front face of a window covering as shown in FIG. 3.

FIG. 5 is a front elevational view of the front face of a window covering of FIG. 1, shown in a fully closed, pulled-down position.

FIG. 6 is a side elevational view of the front face of a window covering as shown in FIG. 5; and,

FIG. 7 is a plan view of a single panel of the front face of a window covering shown separate from the remainder of the design as shown in FIG. 1 for clarity of illustration.

The broken line showing of a back face of a window covering in FIGS. 1-6 is environmental only and forms no part of the claimed design. The design pattern shown in the front elevational and plan views continues throughout the length and width of the front face of the window covering. The front face of the window covering is shown broken-away both vertically and horizontally in the front elevational views and broken-away vertically in the side elevational views to indicate that a specific length and width form no part of the claimed design; and the single panel of the front face of the window covering is shown broken away horizontally to indicate that a specific width forms no part of the claimed design.

The dots and wavy lines on the surface of the front face of a window covering are a pattern on that surface, which is a translucent material. Due to this translucency, the density of the dots upon the individual panels of the front face of the window covering changes between the FIG. 1, FIG. 3, and FIG. 5 views, in order to reflect the portion of the panel, or panels, behind the outermost panels and visible through them. The overlaps between these panels are depicted in the FIG. 2, FIG. 4, and FIG. 6 views.
